UNITED STATES PATENT OFFICE.

JOHN W. ANDERSON, OF CHICAGO, ILLINOIS, ASSIGNOR OF ONE-HALF TO CLARENCE POFFENBERGER, OF CHICAGO, ILLINOIS, AND ONE-HALF TO CORBER COMPANY, OF AURORA, ILLINOIS, A CORPORATION OF ILLINOIS.

CONCEALED DOOR HINGE.

Application filed April 25, 1921. Serial No. 464,195.

To all whom it may concern:

Be it known that I, JOHN W. ANDERSON, a citizen of the United States, residing at Chicago, in the county of Cook and State 5 of Illinois, have invented a certain new and useful Improvement in Concealed Door Hinges, of which the following is a full, clear, concise, and exact description, reference being had to the accompanying drawings, forming a part of this specification.

This invention relates to improvements in concealed door hinges.

In many arts, particularly the automobile body art, it is highly essential that hinges 15 of a concealed type be employed in order to maintain a thoroughly finished appearance and avoid unsightly projections. Concealed hinges, broadly, have heretofore been used, particularly on automobiles. Many difficulties 20 have been experienced with former types of such concealed hinges used in the trade, particularly with respect to the assembling of the parts of the hinges after the parts have been attached to the body and door 25 respectively and in providing ample clearance between the adjacent parts of the body and door as the door swings to open position. Furthermore, such concealed hinges 30 for the purpose indicated that have been used heretofore, have been almost necessarily limited to use on automobiles having bodies of a more expensive type and employing heavy door posts and edge pieces on the door 35 for the reason that, all of such concealed hinges have, so far as I am aware, necessitated mortising for a depth of at least an inch and generally more, into the wood door pieces. Obviously, when the wood door 40 pieces require mortising to such a depth, they must be of considerable width and depth in order to retain any appreciable strength in the portions of the wood surrounding the mortise.

One object of my invention is to provide a 45 concealed hinge, especially adapted for use on automobile bodies, which does not require mortising to any extent into the woodwork to the end that the hinges may be applied on bodies employing lighter wood pieces 50 without destroying their strength and wherein is also obtained ample clearance in the swinging movements of the door so as to positively avoid any marring of the finish.

Another object of my invention is to provide a concealed hinge of the strap type. 55

Another object of the invention is to provide a concealed hinge especially adapted for automobile bodies wherein the parts may be readily assembled and thereafter locked in operative position after the parts of the 60 hinge have been secured to the body and door respectively.

Other objects of the invention will more clearly appear from the description and claims hereinafter following. 65

In the drawings forming a part of this specification, Figure 1 is a horizontal, sectional view taken through a portion of a door and surrounding relatively stationary door frame as for instance on an automobile 70 body. The dotted lines indicate the door swung to fully open position. Figures 2 and 3 are vertical, sectional views corresponding respectively to the section lines 2-2 and 3-3 of Figure 1. Figure 4 is an 75 elevational view of one of the hinge plates or strap. Figure 5 is an elevational view of a block detached, which is employed in the improved hinge. Figure 6 is a horizontal, sectional view illustrating more particularly the manner of assembling the parts of the hinge after the parts have been secured to the door and door frame respectively. Figure 7 is a vertical sectional view taken 80 through an automobile body illustrating the 85 advantages of my improved hinge as applied to those car bodies having inturns at the bottom. And Figure 8 is a horizontal sectional view taken through a portion of one 90 of the doors, detached, showing the hinge elements carried thereby in plan.

In said drawings, 10 denotes a portion of a door the edge of which is opposite the edge of the automobile body proper 11, when the hinge is employed on an automobile. As 95 customary, the door is generally provided on the outer side thereof with a molding strip 10^a and the body with a molding or beading strip 11^a, the same overlapping the usual small gap left between the opposed edges of the door and body when the door is in closed position. Ordinarily a slight gap 12 is left between the two pieces of molding or beading, said gaps being left on account 100 of the fact that a cushion is ordinarily used against the free edge of the door requiring 105

some slight movement of the door as it is forced to closed position.

The improved hinge, as shown, comprises, broadly, two main members or plates or straps designated A and B, respectively; a link C; a second link D; a pivot block E; and a locking screw F.

The plate A is preferably of rectangular form and of a thickness approximating 10 $\frac{3}{8}$ " to $\frac{1}{2}$ " and is adapted to be secured to the body by means of four wood screws 13-13, said screws 13-13 passing through openings 14-14 provided in the relatively thin bottom wall 15 of the plate A, said wall 15 resulting from the formation of a rectangular recess 16 formed on the outer side of the plate A. As shown in Figures 1 and 3, the heads of said screws 13 are countersunk flush with the inner face of the 20 back wall.

The other plate or strap B, which is preferably secured to the door 10, is also of rectangular form and of appreciably lesser thickness than the plate A, the thickness 25 of the plate B approximating a quarter inch. Said plate B is secured to the door also preferably by four countersunk wood screws 17-17. On account of the relatively shallow thicknesses of the plates A 30 and B, it is evident that it is unnecessary to provide any deep mortises within either the body or the door wood members and consequently the latter may be of comparatively small dimensions without militating 35 against their strength after the hinges are applied. The plates A and B are preferably countersunk flush with the surfaces of the respective parts to which they are secured merely by cutting transversely extending 40 slots 18 and 19 respectively in the wood parts to which they are secured.

As best shown in Figures 1, 2 and 4, the plate A, within the recess 16, is provided near the outer side of said plate with a centrally disposed integral lug 20 which has a rounded slightly inclined outer end 20^a spaced a short distance from the adjacent slightly oppositely inclined face 16^a defining one side of the recess 16. The lug 20 50 is apertured as indicated at 21 and threaded to receive the screw F and the top face of the lug 20, surrounding the aperture 21 is suitably beveled as indicated at 21^a to fit the under side of the head of the screw F 55 so that, when the screw F is screwed home, as shown in Figures 1 and 2, the top face of the head of the screw F will lie flush or within the outer face of the plate A.

The plate B is formed with a preferably 60 integral transversely extending lug 22 on that end of said plate B remote from the lug 20, that is, near the inner side of the door 10. In this connection, it will be understood that the outer side of the door 65 and body is that side to which the door

swings. Said lug 22 is of a length such that it will be readily received within the recess 16 of the plate A when the door is in closed position, as shown in Figures 1 and 3. The lug 22 is cut away at its center as indicated at 23 in Figure 3 so as to thereby provide spaced arms 24-24 to receive the ends of a pivot pin or pintle 25 by which the adjacent narrowed end 26 of the link C may be pivotally attached.

The opposite end of said link C is cut away at its center so as to provide a forked construction having two arms or tines 27-27 as best shown in Figure 2, said arms 27 being pivotally connected to the block C by short pivot pins or pintles 28-28. As best shown in Figure 5, said block E is suitably recessed at each end thereof to provide pairs of spaced flanges 29-29 between which said arms 27 are received and by which said pins 28 are supported.

The link D, which is centrally disposed with respect to the plate B, is pivotally connected to the latter by means of a suitable hinge pin or pintle 30 extending through said link D and a pair of spaced lugs 31-31 formed integrally with the plate B. The plate B is provided with a longitudinally extending centrally disposed recess 32 within which said link D is partially accommodated when the door is in closed position, as best shown in Figure 1. The opposite end is pivotally connected to the block E by means of a pivot pin or pintle 33, the ends of the latter being carried by extensions 29^a-29^a of the two inner flanges 29-29.

The block E, is formed on its outer side, that is the side nearest the outer sides of the door and body, with a slightly sloping face 34 conforming to and adapted to fit against the sloping face 16^a of the plate A. Said block E is also formed with a flat inner face 35 fitting against the flat bottom of the recess 16 of said plate A. The length of the block E is made slightly greater than the width of the major portion of the recess 16 and the latter is laterally enlarged to accommodate the ends of said block E, as indicated best at 16^b-16^b, in Figure 4. At its center, the block E, is longitudinally recessed as indicated at 36 so as to snugly straddle the lug 20, the arms 37-37 formed by said recess 36 being partially caught under the large head of the screw F when the block is in place. By tightening the screw F, it is evident that the block E will be held securely in place and by unscrewing the screw F, the block E may be released and the parts readily separated.

As best shown in Figure 6, after the plates A and B have been secured to the body and the door, respectively, it being understood that the links C and D have previously been attached to the plate B and the

block E, the parts of the hinge may be assembled by slipping the block E under the head of the loosened screw F at an angle while the door itself extends at an angle less than a right angle with respect to the body wall and, as fully shown in Figure 6, the projecting molding strip 10^a of the door will be far enough away from the beading strip 11^a and main surface of the body to avoid any possibility of the one being scratched or marred by the other. After the block E is slipped beneath the screw F, the latter is tightened and the parts thereby securely locked in operative relation.

Referring now more particularly to Figures 1 and 6, it will be noted that the axis of the pivot pin 25 is offset outwardly from the plate B whereas the axis of the pivot pin 30 is approximately in line with the exposed face of the plate B and also that the last named pivotal axis is located approximately $\frac{3}{8}$ " nearer the outer side of the door. At the opposite ends of said links C and D, and considering the block E as a rigid or substantially integral part of the plate A, the axes of the pivot pins 28 by which the link C is secured to the plate A, are substantially in line with the plane of the exposed face of the plate A whereas the axis of the pivot pin 33 by which the link D is connected to the plate A, is outside of the plate A and nearer the outer end of said plate A. Furthermore, the effective swinging length or radius of the link C is made a little greater than the effective swinging length or radius of the link D. With the arrangement and location of links and pivotal axes above described, it will be seen that the door and plate B in an opening swinging movement do not oscillate with respect to any single axis but on the contrary swing about two sets of axes, the relation of which gradually varies during the opening movements of the door. The arrangement is such that, as the door starts its opening movement, both the outer end and the inner end of the plate B are initially moved away from the plate A, the inner end of the plate B moving away at a somewhat faster rate than the outer end of the plate B. This insures the necessary clearance between the beads or moldings of the door and body so as to avoid any possible rubbing of the one on the other. The movement of the outer end of the plate B away from the plate A continues, in conjunction with its swinging movement also, until the links C and D begin to partially overlap each other at the forked end of the link C and thereafter the general direction of travel of the plate B is approximately about the axis of the pivot pin 33 until the door reaches a position substantially at right angles to the body wall. As clearly

shown in Figure 1, there is an unusual amount of clearance between the parts of the door and the body when the door is open, thus positively eliminating any danger of the parts rubbing or scratching each other. The limit of the opening movement of the door is determined by the two links C and D having the portions 38 and 39 thereof coming into contact, as shown in Figures 1 and 6. With the arrangement and operation above described, it is evident that the plates or straps of the hinge are concealed when the door is in closed position and so far as I am aware, no one heretofore has ever devised a hinge of the strap type which may be concealed and I intend to claim the same broadly.

Referring to the illustration of an automobile body inturned at its bottom, as illustrated in Figure 7, it will be noted that my improved hinge possesses very important advantages over the usual type of concealed hinges requiring mortising within the wood-work. As well understood by those skilled in the art, the upper and lower hinges of a door must have their effective axes of oscillation in vertical alinement. Where the lower part of a car body is inturned, which is extremely common in automobile practice, it has generally been the custom to employ a strap hinge which projects outwardly from the body for a lower hinge. It is evident that, if a concealed hinge requiring mortising of the woodwork were employed for the lower hinge, the mortise for the same would come so far out on the woodwork in order to bring it into vertical alinement with the upper hinge, that the woodwork would be substantially entirely cut away for such lower hinge and thereby weaken the wood-work or in fact partially expose the lower hinge. With my construction, where the plates or straps of the hinge do not require the mortising of the woodwork, and where the amplitude or throw of the moving door is as great as shown and described, the upper hinge may be placed at the extreme limit inwardly of the body and door and the lower hinge placed at the extreme limit outwardly of the body and door without weakening the woodwork and leaving ample clearance between the open door and the body at the top part of the door when open. It is believed that this will be clearly understood from the disclosure of Figure 7 without further detailed explanation.

In actual practice, the plates or straps A and B will be originally made with an excess of metal at each end thereof, such excess portions being indicated by dotted lines in Figure 4 of the drawing and references X—X. The purpose of this is to permit such portions of said excess metal being cut off at either or both ends as may be found necessary to bring the ends of the plates flush.

with the woodwork and dependent upon whether the hinge is a top hinge or a bottom hinge. In Figure 7 of the drawing, the excess portion of the plate A secured to the body at the top which would be cut off as indicated at Y on one side and Y' on the other side, it being noted that practically all of the excess metal in the portion Y would be cut off whereas only a part of the portion Y' would be cut off. In the case of the lower hinge, the excess portions which would be cut off are indicated at Z and Z'. The portion Z, at the right is obviously much narrower than the corresponding portion Y of the upper hinge whereas the portion Z' cut off on the lower hinge is considerably in excess of the corresponding portion Y' of the upper hinge. Furthermore, it will be noted that the left hand edge of the plate A for the lower hinge may be milled to conform to the curvature of the body at that point without affecting the successful application and operation of the hinge.

I have found that my type of concealed strap hinge may be successfully employed on automobile bodies for both the upper and lower hinges where the incurve or inturn of the body at the bottom amounts to as much as five to seven inches and that the door will swing clear of the car body in its opening movements, as shown in Figure 7 which accurately reproduces an actual example of the use of my hinges as applied to a body having an incurve or inturn of seven inches. It will be noted that there is ample clearance between the door and body, when the door is open, throughout the entire length of the parts.

I have herein shown and described what I now consider the preferred manner of carrying out the invention but the same is merely illustrative and I contemplate all changes and modifications that come within the scope of the claims appended hereto.

45 I claim:

1. In a hinge of the character described, the combination with two members adapted to be secured to the opposed edges of a stationary door frame and a door respectively; of a pair of connecting links between said members, one set of ends of said links being pivotally connected to one of said members and the remaining set of ends being pivotally connected to the other member, and the pivotal connections at opposite ends of one of said links being offset in the same direction laterally of the door with reference to the corresponding pivotal connections at the opposite ends of the other link, when the door is closed.

2. In a hinge of the character described, the combination with two members adapted to be secured to the opposed edges of a stationary door frame and a door, respectively; of a pair of connecting links between said

members, one set of ends of said links being pivotally connected to one of said members at non-axially aligned points, the remaining opposite sets of ends of the links being pivotally connected to the other member also at non-axially aligned points, the distance between the axes of the pivotal connections of one of said links being less than the distance between the axes of pivotal connections of the other of said links, said links being arranged to operate in separate planes.

3. In a hinge of the character described, the combination with two plates adapted to be secured to the opposite edges of a relatively stationary door frame and a door respectively; of two separate means, each means being pivotally connected with each plate, none of the axes of the pivotal connections being aligned and each means being also rigid between its points of pivotal connections with the plates, said pivotal connections of one means being offset transversely with respect to the pivotal connections of the other means to an extent to compel said links to swing to folded transverse position entirely between said opposed edges when the door is closed.

4. In a hinge of the character described, the combination with two plates adapted to be secured to the opposed edges of a relatively stationary door frame and a door, respectively; of two separate elements each pivotally connected with each plate, none of the axes of the pivotal connections being aligned, the points of pivotal connections of both of said means to one of said plates being located relatively near that end of said plate which is nearest the outer face of the door and the points of pivotal connection of said means to the other of said plates being located relatively near the opposite end of said other plate, said elements being arranged so that portions of one of the same extend within the plane defined by the other when said door is in closed position.

5. In a hinge of the character described, the combination with two plates adapted to be secured to the opposed edges of a relatively stationary door frame and a door, respectively; of two separate means each directly pivotally connected with each plate, for swinging movement only, none of the axes of the pivotal connections being aligned, the effective radius of swing between the said pivotal connections of one of said means being less than that of the other of said means, said means being in all positions thereof disposed entirely between said door and frame.

6. In a hinge adapted to swingingly connect a door to a door frame and in which the door swings to one side only of the door frame, the combination with two members adapted to be secured to the opposed edges of the door and door frame; of two links

- extending between said members, each link being pivotally connected at its ends to both plates and adapted to swing outwardly beyond said side of the door frame, the two 5 pivotal connections of said links at one set of corresponding ends being axially offset, one of said two pivotal connections being nearer than the other to that end of the corresponding plate which extends toward 10 said side of the door frame and the effective swinging length of said link having its said pivotal connection nearer said end of the plate being less than the effective swinging length of the other of the links.
- 15 7. In a hinge of the character described, the combination with two members adapted to be secured to the opposed edges of a relatively stationary door frame and a door, respectively; of a pair of links, each of 20 which, at one of its ends, is pivotally connected to one of said members; a block to which the other ends of said links are pivotally connected; and means for detachably securing said block to the transverse face of 25 the other of said members.
8. In a hinge of the character described, the combination with two members adapted to be secured to the opposed edges of a relatively stationary door frame and a door, respectively; of a pair of links, each of 30 which, at one of its ends, is pivotally connected to one of said members; a block to which the other ends of said links are pivotally connected; and means for detachably 35 securing said block to the other of said members, said means including a lug on said other member, a slot in the block adapting the block to fit over said lug, and a clamping screw.
- 40 9. In a hinge adapted to swingingly connect a door to a door frame and in which the door swings to one side only of the door frame, the combination with two members adapted to be secured to the opposed edges 45 of the door and door frame; of two links extending between said members, and both adapted to swing to said side of the door frame each link being pivotally connected at its ends to both plates, the two pivotal 50 connections of said links at one set of corresponding ends being axially offset, one of said two pivotal connections being nearer 55 than the other to that end of the corresponding plate which extends toward said side of the door frame and the effective swinging length of said link having its said pivotal 60 connection nearer said end of the plate being less than the effective swinging of the other of the links, said links having cooperating portions in the same path of swinging movement at the ends thereof adjacent the door arranged to engage each other at a predetermined limit of opening movement of the door.
10. In an arrangement of the character 65 described, the combination with a member having a door opening defined in part by a door post and a swinging door, said door post and door having opposed edges when the door is closed and said member and door having moldings adjacent said opposed edges of the door and post and overlapping the joint when the door is in closed position; of a concealed strap hinge having parts secured to the door post and the door respectively and covered by said moldings when the door is closed, said hinge including means pivotally connecting said parts adapted to lie folded transversely of said door when closed and arranged to cause the 80 door to swing about a multiple of different pivot points, the adjacent pivotal points being offset transversely relatively to said door and post.
11. A hinge of the character described 85 comprising: two relatively flat plates adapted to be secured to a door frame and a door respectively, one of said plates being recessed on its exposed side and provided with a lug within said recess; a block 90 adapted to be detachably secured to said lug within said recess and held against turning movement with respect to the recessed plate; a pair of links pivotally connected at non-alined points to said block, one of said links 95 having an effective length shorter than that of the other; and means for pivotally connecting the opposite ends of said links to the other said plates at non-alined points.
12. A hinge adapted for attachment to 100 the opposed edges of a door and a door frame respectively, wherein the door is adapted to swing outwardly to one side of said frame, said hinge comprising a plurality of members foldable side by side when 105 the door is in closed position, two of said members being in the form of plates fixed to the transverse edges of the door and the door frame respectively, and the remaining members being in the form of links each having 110 one end pivotally connected to one of said plates at the end thereof at the inner side of the door and having the other end thereof pivotally connected to the other plate at the 115 end thereof at the outer side of said door frame.
13. In a hinge of the character described, the combination with a relatively stationary door frame and a door member; of two separate means, each means being pivotally 120 connected with the door member and with the frame member respectively, the pivotal connections of said two separate means with each of said members being offset with respect to each other laterally of the door to positively control the swinging movement of the door in a predetermined path, said means being so proportioned and ar- 125

ranged that one of the same projects within the plane defined by the other of said means when the door is in closed position.

14. In a hinge of the character described, 5 the combination with a relatively stationary door frame and door; of two separate links, each link being pivotally connected with said frame and door, the pivots of one of said links being transversely offset relative to the pivots of the other link and offset in the same direction to dispose said links in folded condition between the adjacent opposed edges of the frame and door when closed, said opposed edges being 15 spaced apart a distance less than the length of either of said links.

15. In a hinge of the character described, 20 the combination with a relatively stationary door frame and a door respectively; of relatively long extensions adjacent opposite sides of said frame and door, said extensions being transversely alined when the door is in closed position, and other relatively shorter extensions, one of which is formed 25 on said frame adjacent the other extension thereof, and the other of said shorter extensions being formed adjacent the extension on said door; and separate means, one of which is pivotally connected to the

longer extension on said frame and to the 30 shorter extension on said door, and the other of which is pivotally connected to the shorter extension on said frame, and the longer extension on said door.

16. In a hinge of the character described, 35 the combination with a stationary door frame and a door respectively; of two separate means each pivotally connected with said door and frame, on non-coincident parallel axes, and the pivotal axes of one of 40 said means being disposed in a common plane to one side of the plane common to the pivotal axes of the pivots of the other means said frame being provided with a recess for the reception of one of said means, 45 and the door being provided with a recess for the accommodation of the other of said means when the door is closed the space between the opposed inner wall of said recesses when said door is closed being less than the 50 distance between the pivotal connections at the opposite ends of either of said pivoted means.

In witness that I claim the foregoing I have hereunto subscribed my name this 19th 55 day of Apr. 1921.

JOHN W. ANDERSON.
